UNITED STATES PATENT OFFICE.

MARTIN L. DODGE, OF LAKE KUSHAQUA, NEW YORK, ASSIGNOR OF ONE-HALF TO
ALBERT E. PAYE, OF LAKE KUSHAQUA, NEW YORK.

BOOKREST FOR HOSPITAL-BEDS AND CHAIRS.

1,384,744.

Specification of Letters Patent. Patented July 19, 1921.

Application filed April 12, 1920. Serial No. 373,270.

To all whom it may concern:

Be it known that I, MARTIN L. DODGE, a citizen of the United States of America, residing at Lake Kushqua, in the county of 5 Franklin and State of New York, have invented certain new and useful Improvements in Bookrests for Hospital-Beds and Chairs, of which the following is a specification.

My present invention relates generally to 10 book rests, and more particularly to book rests for chairs, stands, tables, beds and the like, my object being the provision of an improved arrangement and construction as presently to be described with respect to the 15 accompanying drawings.

In these drawings, which form a part of this specification and illustrate two forms of the invention,

Figure 1 is a sectional elevation illustrating the practical application of my invention to bed rails,

Fig. 2 is a vertical section through the rest plate taken on line 2-2 of Fig. 1,

Fig. 3 is a horizontal section through the 25 rail clamp taken on line 3-3 of Fig. 1,

Fig. 4 is a vertical section taken on line 4-4 of Fig. 1,

Fig. 5 is a vertical section taken centrally through Fig. 4,

Fig. 6 is a view partly in elevation and partly broken away and in section of a modified form applicable to tables, chairs and stands,

Fig. 7 is a vertical section taken on line 35 7-7 of Fig. 6, and

Fig. 8 is a top plan view of the clamp.

Referring now to these figures and particularly to Figs. 1 to 5 inclusive, I propose a book rest supported by a bed rail engaging clamp, a bed rail being seen at 10 in Fig. 1, of the usual angular type. The clamp consists of a pair of angular clamping blocks 11 and 12, the block 11 being adjustable in the angle of the block 12 and in a 45 vertical direction by virtue of a vertical adjusting bolt 13 which extends upwardly through the inner body portion of block 11 from the underlying extension 14 of the block 12 as best seen in Fig. 5. This bolt 50 has an intermediate offset 15 and receives an upper clamping nut 16 bearing on the block 11.

The lower portion of the body of block 11, whose inner face slides vertically along the 55 inner face of the body of block 12 on guide

pins 11^a, has a slot 17 through which the inner portion of a horizontal adjusting bolt 18 extends, the inner end of this bolt carries a clamping plate 19 and its outer portion extends outwardly through an opening 60 in the body of block 12 and is threaded through nuts 20 stationarily embedded in said block. This bolt has an outer winged head 21 by means of which it may be conveniently rotated to advance or retard the 65 clamping plate 19, depending upon the direction of such rotation.

The rail engaging extension 11^b of block 11, has an angle plate 22 which depends therebelow and the extension 14 of block 12 70 has an upstanding plate 23. These depending and upstanding portions of the plates 22 and 23 oppose the clamping plate 19 so that a bed rail 10 may be received and clamped vertically between the block extensions 11^b and 14 and clamped horizontally between the block carried plates 22 and 23 and the clamping plate 19, as clearly seen by a comparison of Figs. 1 and 4.

As seen particularly in Fig. 5, the 80 block 12 has an upper socket 24 in which is stepped the lower reduced end 25 of a standard 26 having adjacent to its upper end a U-strap 27 slidably embracing a vertical lengthwise adjustable arm 28 intermediate the ends of the latter. This vertical arm has a lengthwise slot 29 and is provided at its lower end with a U-strap 30 slidably embracing the standard 26, the slot 29 receiving therethrough the threaded end 90 of a clamping bolt 31 mounted through the upper portion of the standard 26 and whose free end is engaged by a wing nut 32 for securing the arm 28 in vertically adjusted position.

To the upper end of the vertical arm 28 95 is secured one end of a horizontal arm 33, the opposite end of which as best seen in Figs. 1 and 2 is secured to the lower end of an upright 34.

The upright 34 is longitudinally slotted from its upper end and for the major portion of its length, and its extensions 35 upon opposite sides of the slot have a transverse clamping bolt 36 extending therethrough adjacent to their free ends and receiving a wing nut 37, bolt 36 also passing through the central enlarged portion 38 of the rest plate rib 39 which is shiftable at its lower portion more or less into the space be- 110

tween the upright extensions 35 as the inclination of the rest plate 40 is varied with respect to the upright 34. The rest plate 40 vertically along the rear face of which the 5 rib 39 is secured, may thus be secured in adjusted position by tightening the wing nut 37.

The rest plate 40 has a forwardly extending flange 41 along its lower edge and is 10 provided with a transverse book holding wire 42 projecting across its face above the flange 41, the said wire being preferably of the inverted U-shape shown, with angular extensions 43 at its extremities bent into 15 and securely embedded in the side edges of the rest plate 40.

It is thus obvious that with the clamping device previously described engaged with the bed rail 10, the horizontal supporting arm 33 offsets the rest plate 40 to a 20 position in front of a patient or occupant of the bed, the relative adjustment of the vertical arm 28 with respect to the standard 26 permitting the rest plate to be 25 adjusted vertically to the proper height, and the movement of the rest plate 40 on the pivot and clamping bolt 36 permitting the rest plate to be adjusted to the desired inclination.

30 In the form of the invention shown in Figs. 6, 7 and 8 the rest plate 40^a with its book holding wire 42^a lower flange 41^a and rib 39^a with its central enlarged portion 38^a are the same as previously described as 35 is also the construction of the upright 34^a with the clamping pivot bolt 36^a and wing nut 37^a. Likewise the upright 34^a is similarly connected at its lower end to a horizontal offsetting arm 33^a the latter being 40 however in this instance directly connected to the inner body portion 44 of a clamping block by means of a clamping bolt 45 which passes vertically through the said body portion and through the outer end of the arm 45 33 to receive a clamping wing nut 46 upon its upper threaded end.

The body portion 44 of the clamping block just above referred to has an upper outer extension 47 which overlies a second clamping block 48 having a lower laterally and in-

wardly projecting clamping plate 49 which opposes the lower surface of the body portion 44 of the first clamping block so as to provide for the mounting of the clamp as a whole by engagement of the arm of a chair 55 or the side edge of a table, stand and the like between these parts. For this purpose the clamping block 48 has a vertical clamping bolt 56 which projects upwardly through the extension 47 of the other clamping block 60 and receives a winged clamping nut 51. Thus the construction last described differs from the first construction in respect to the particular form of the clamping blocks or members and the particular connections between the clamp and the horizontal supporting arm of the book rest plate, the book rest plate and its horizontal supporting arm being swingable in the form of Figs. 6, 7 and 8 by virtue of the bolted connection at 70 45 directly with one of the clamping blocks and being similarly swingable in the form of Figs. 1 to 5 inclusive by virtue of the stepping or tenoning of the lower end of the standard 26 into the upper portion of the 75 clamping block 12.

My invention according to both of these constructions provides for ready convenient attachment of the device as well as its easy 80 convenient manipulation and adjustment in use, and is at the same time simple, inexpensive and durable.

I claim:

A book rest including an adjustable rest plate and a supporting clamp from which 85 the rest plate is adjustably mounted, said clamp including a pair of L-shaped blocks in adjustable connection with one another, having spaced parallel extensions one of which projects beyond the other, a clamping 90 plate, plates secured to the ends of said block extensions and projecting inwardly therefrom and each opposing a portion of the said clamping plate, and an adjusting member working through a bore in one 95 block and a slot in the other block as and for the purpose set forth.

In testimony whereof I have affixed my signature.

MARTIN L. DODGE.
